SEGMENTAL TUBE SHEET

John W. Throckmorton and John S. Wallis, New York, N. Y., assignors to Petro-Chem Process Company Incorporated, New York, N. Y., a corporation of Delaware

Application December 15, 1948, Serial No. 65,474

5 Claims. (Cl. 122—510)

1

This invention relates to tube sheets or other supports for furnaces and similar structures in which the tubes are arranged in circular or other formations such as elliptical, or rectangular with rounded ends, and is an improvement on our Patent No. 2,340,287, issued February 1, 1944.

Heretofore the tube supports have been special for each size of furnace, even when the tubes were of the same size. For example, a tube sheet for 80 tubes arranged in a circle of 8 feet in diameter was entirely unsuitable for use in a furnace of 150 tubes arranged in a circle of 12 feet in diameter.

An object of the invention is to provide a tube sheet formed of segmental units so shaped as to permit them to be built up into continuous gas-tight sheets or endless chains adapted to furnaces of different sizes and shapes. The segmental units may be carried in stock and a greater or lesser number of them used depending upon the furnace size and the number of tubes distributed about the combustion chamber.

Our invention has the advantage of greatly reducing the size and bulk of the tube sheet parts and moreover makes it possible to readily replace tubes after the structure has been in operation. For example, in cracking furnaces, tubes are sometimes burned out and have to be replaced. This can readily be done by replacing only the tube sheet segments which cooperate with the damaged tubes.

The tube sheet segments are small and uniform, and can be cast from a single pattern or from relatively few patterns, and large quantities may be carried in stock at small expense.

Further and other objects and advantages will be apparent from the specification and claims, and from the accompanying drawings which illustrate what is now considered the preferred embodiment of the invention.

In the drawings:

Fig. 1 is an elevational view of a cylindrical furnace with parts in section indicating location of the segmental tube sheets;

Fig. 2 is an enlarged section of the upper-tube-sheet portion of the furnace shown in Fig. 1;

Fig. 3 is an enlarged section of the lower-tube-sheet portion of the same furnace;

Fig. 4 is an enlarged plan of a portion of the upper-tube-sheet of the furnace shown in Fig. 1;

2

Fig. 5 is an enlarged detail of one of the segment plates shown in Fig. 4;

Fig. 6 is a sectional view taken on line 6—6 of Fig. 5;

Fig. 7 is an enlarged plan of a portion of the lower-tube-sheet of the furnace shown in Fig. 1;

Fig. 8 is an enlarged detail of the segment plates shown in Fig. 7;

Fig. 9 is a sectional view on line 9—9 of Fig. 8;

10 Fig. 10 is a modified form of segment plate for use in the lower tube sheets;

Fig. 11 is a sectional view on line 11—11 of Fig. 10;

Fig. 12 is an illustration of the invention applied to a large multi-burner furnace with straight sides and rounded ends; and

Fig. 13 is an illustration of the invention applied to a large furnace of elliptical cross-section.

15 As illustrated in Fig. 1, upon frame members 10 is mounted a combustion chamber comprising an inner wall 11 of fire brick, surrounded by insulation 12, and a metallic shell 13. Burners 14 furnish heat to the ring of tubes 15 near the wall of the combustion chamber.

Breeching 16 supports a stack 17. A vertical plate 18 within the breeching supports an angle-ring 19. On shell 13 at a height corresponding to that of ring 19 is a support ring 20, and the upper ends of tubes 15 extend between those rings.

The tube sheet is made up of a chain of segments or plates 21 (Figs. 5 and 6), supported by rings 19 and 20. Each segment 21 has a body portion designed to lie in a predetermined plane and is of essentially hexagonal shape in said plane. The body portion includes two opposite pairs of adjacent shoulders 21a and 21b.

A first pair of adjacent extension wing structures 21a projects from the pair of adjacent hexagonal shoulders 21b and has a face that is parallel to said plane. A second pair of adjacent extension wing structures 21b projects from the pair of adjacent hexagonal shoulders 21a (which is opposite the pair of shoulders 21b) and has a face that is parallel to said plane. The wing structures 21a and 21b of each segment 21 are respectively adapted to overlap and underlap the wing structures 21b and 21a of adjoining segments 21, to form slip-joints between the

segments. The wing structures $21a$ and $21h$ are substantially half the plate thickness.

Each of the wing structures $21a$ and $21h$ has outer edges $21e$ and $21f$, respectively. The two edges $21e$ are contoured to define a reentrant angle which has its apex close to the apex of the angle formed by the shoulders $21b$, and which is larger than the last mentioned angle. Similarly, the two edges $21f$ are contoured to define a reentrant angle which has its apex close to the apex of the angle formed by the shoulders $21g$, and which is larger than the last mentioned angle.

Each of two semicircular recesses is perpendicular to the plane of the segment 21 . One recess intersects the edges $21e$ of the wing structure $21a$, and the other recess intersects the edges $21f$ of the wing structure $21h$. Each recess extends partially into the body portion, so that the apices of the angles defined by the shoulders $21b$ and the edges $21e$ lie within one recess, and the angles defined by the shoulders $21g$ and the edges $21f$ lie within the other recess. Each recess is adapted for cooperation with a like recess in an adjoining segment, to fit around a tube when the adjoining segments are abutted together with their adjacent pairs of wing structures dovetailed.

Wings $21a$ and $21h$ and shoulders $21b$ and $21g$ are so shaped as to permit angular plate adjustment according to the tube circle diameter, while the webs or wings provide a complete overlapping closure, also independent of tube circle diameter. Each segment is stiffened by a rib $21c$. Notches $21d$ in the edges of the segments accommodate bolts 22 which hold the plates in their adjusted positions on rings 19 and 20 .

At the bottom of the combustion chamber, outside the tubes, is a ring 23 (Fig. 3), while within the tube circle is a cooperating ring 24 welded at 25 to the fire pot frame. Rings 23 and 24 support segmental plates 26 (Figs. 8 and 9). These plates have openings to accommodate the lower circular bosses $27a$ of return-bends 27 . Plates 26 have wing members $26a$ corresponding to the wings $21a$ of plates 21 . Annular shoulders $26b$ likewise correspond to shoulders $21b$ of plates 21 . Plates 26 have two stiffening ribs $26c$. Notches $26d$ accommodate anchor bolts 22 .

In place of segment plates 26 serving as a bottom tube sheet, there may be used a modified type of segment shown at 28 in Figs. 10 and 11. In this design the lower return-bend fittings 27 rest in depressions $28e$ in the segments. This design has wing members $28a$, shoulders $28b$, ribs $28c$ and bolt-receiving notches $28d$. Apertures in depression $28e$ accommodate the plugs in the bottom of the return-bend fittings. Where an inlet and outlet connection is made at the bottom of the tube bank, a segmental plate such as that shown at 29 in Fig. 7 is used. This plate has two apertures for tubes, one on each side of reinforcing rib $29c$.

Figs. 12 and 13 illustrate the use of the above described segment plates 21 in large furnaces in which burners are indicated at 30 and the wall curvature varies through a wide range from short arcs to straight sides.

It is to be understood that the invention is not limited to the specific embodiments herein illustrated and described, but may be used in other ways without departure from its spirit as defined by the following claims.

What is claimed is:

1. A tube sheet for supporting a curved bank

of parallel tubes in predetermined spaced relation, comprising a chain of successively abutting segments, said chain lying in a predetermined plane, each segment comprising a body having an essentially hexagonal shape in said plane, and having two opposite pairs of adjacent hexagonal shoulders respectively disposed to constitute its ends adjacent the next segments, and the said shoulders of each end defining an angle pointing toward the corresponding adjacent segment, and wing extension structures integrally projecting from the said ends of the body and having faces parallel to said predetermined plane and overlapping in flatwise abutment the faces of corresponding complementarily disposed extension structures of the adjacent segments, each pair of adjacent wing extension structures defining at its end a reentrant angle which is larger than the angle formed by the hexagonal shoulders of the adjacent body, so as to receive said last mentioned shoulders within said reentrant angle while permitting angular adjustment of the adjacent segments relative to each other, and each segment being apertured for tube support so that the chain is collectively adapted to support the tubes in the aforesaid spaced relation.

2. A tube sheet as described in claim 1 wherein each segment is apertured by a pair of essentially semi-circular recesses disposed centrally of the respective ends of the segment and cooperating with the recesses of the adjacent segments to receive tubes at regions centrally intersecting the overlapped wing extension structures.

3. A tube sheet as described in claim 1 wherein in each segment is apertured by a pair of spaced holes disposed centrally of the body and each dimensioned to receive a tube, said holes lying in a path extending between the midpoints of the ends of the body.

4. A tube sheet as described in claim 1 wherein in each segment is apertured by a hole disposed centrally of the body and dimensioned to receive a tube.

5. A segment for a tube sheet to be composed of a chain of such segments in successively abutting relation, comprising a body portion designed to lie in a predetermined plane and having an essentially hexagonal shape in said plane, a pair of adjacent extension wing structures projecting from one pair of adjacent hexagonal shoulders and having a face that is parallel to said plane and is adapted to overlap the corresponding face of an adjoining segment in the chain, a second pair of adjacent wing structures projecting from the pair of adjacent hexagonal shoulders which is opposite the first mentioned pair of shoulders, said second pair of wing structures having a face parallel to said plane and similarly adapted to underlap a corresponding face of an adjoining segment, each of said pairs of wing structures having outer edges contoured to define a reentrant angle which has its apex close to the apex of the angle formed by the adjacent pair of hexagonal shoulders on the same end of the body portion and which is larger than said last mentioned angle, two essentially semi-circular recesses perpendicular to said plane and intersecting respectively the outer edges of each pair of wing structures and extending partially into the body portion so that the apices of both said angles lie within one recess, and each recess being adapted for cooperation with a like recess in an adjoining segment, to fit around a tube when the adjoining segments are abutted

together with their adjacent pairs of wing structures dovetailed.
